CLAIM

The ornamental design for a starting fluid injection system canister, as shown and described.

DESCRIPTION

FIG. 1 is a perspective view of a starting fluid injection system canister that incorporates my new design;

FIG. 2 is a front elevational view thereof;

FIG. 3 is a top view thereof;

FIG. 4 is a side elevational view thereof; and,

FIG. 5 is a bottom view thereof.

The back elevational view and the left side elevational view are identical to FIG. 4.
